UNITED STATES PATENT OFFICE.

HENRY T. PAISTE, OF PHILADELPHIA, PENNSYLVANIA, ASSIGNOR TO H. T. PAISTE COMPANY, OF PHILADELPHIA, PENNSYLVANIA, A CORPORATION OF PENNSYLVANIA.

FUSE PLUG.

Application filed February 10, 1920. Serial No. 357,536.

To all whom it may concern:

Be it known that I, HENRY T. PAISTE, a citizen of the United States, residing in Philadelphia, Pennsylvania, have invented

5 Fuse Plugs, of which the following is a specification.

One object of my invention is to provide a fuse plug of the type which includes a renewable fuse-carrying capsule, whose construction shall be such as to insure good contact between the fuse on said capsule and the shell of the plug body even though the capsule shall not be inserted in the latter for its full 10 distance; the invention more particularly 15 contemplating a novel form of contact shell formed and disposed to frictionally engage the fuse when the capsule on which this is carried has been either partially or wholly inserted in the fuse body.

20 Another object of my invention is to provide a fuse plug with a novel form of body structure especially designed to insure the escape of the gases or heated air formed upon the blowing of the fuse by an excessive current; the invention also including a 25 novel form of fuse capsule especially designed to cooperate with suitably formed frictional holding members on a fuse body to insure said body and capsule remaining 30 in frictional engagement until forcibly separated.

These objects and other advantageous ends I attain as hereinafter set forth, reference being had to the accompanying drawings, in which,

Figs. 1 and 2 are respectively a side elevation and a bottom plan of a fuse plug constructed in accordance with my invention;

Fig. 3 is a plan similar to Fig. 2 with the 40 fuse capsule removed;

Fig. 4 is a vertical section on the line 4—4, Fig. 3;

Figs. 5 and 6 are respectively a side elevation and a plan of the fuse capsule;

Fig. 7 is a vertical section on the line 7—7, Fig. 6; and

Fig. 8 is a plan of the fuse body after the cover and its retaining shell have been removed.

50 In the above drawings 1 represents the porcelain or equivalent insulating frame of the body portion of my fuse plug, which is preferably of a generally cylindrical form enlarged and having an outwardly extending flange 2 at one end. This frame is hol-

low, its cavity consisting of a cylindrical portion 3 and a portion 4 of polygonal section, in the present instance hexagonal. The outer face of the flange 2 is radially toothed or corrugated and has mounted upon it one 60 or more mica or other plates 5 of transparent insulating material forming a cover which is held in place by a flanged sheet metal ring 6. The flange 7 of this ring extends over and is slightly spaced away from the sides of the body flange 2 and is spun or turned inwardly at its extremity so that it is permanently retained in place.

An annular recess 8 is formed in the frame structure 1 adjacent the flange 2 for the reception of the inwardly spun edge of one end of a threaded shell 9, forming one of the main contacts of the fuse plug. The second end of this shell is extended inwardly over the smaller end of the frame structure 75 1 and terminates in a series of spring tongues 10 which are projected or bent into the hexagonal portion 4 of the cavity of the frame structure. These tongues are preferably of pointed or triangular form and extend away from the walls of the cavity at an acute angle so as to be more or less yielding and frictionally engage the flat sides of the hexagonal portion 11 of a fuse capsule 80 12 formed of porcelain or other insulating material and also including a cylindrical portion 13 formed to more or less closely fit into the cylindrical part 3 of the cavity in the body.

Said capsule also has at one end an outwardly extending flange 14 of substantially the diameter of the small end of the body and has a substantially cylindrical passage or cavity closed at its flanged end 14 by a metallic contact member 15. This latter 95 has portions extending into the cavity of the capsule where it is connected to one end of the fuse 16. This latter extends through the hollow interior of the capsule and is bent outwardly through a notch 17 in the open or unflanged end thereof, from whence it passes longitudinally over the outside surface of the parts 11 and 13 to the flange 14 where it is bent outwardly at right angles.

This fuse, which is preferably of thin 105 strip material such as zinc, terminates adjacent the outer edge of the flange 14 so that when the capsule is inserted in the hollow 3—4 of the fuse plug body, the outer surfaces of its parts 13 and 11 are frictionally 110

engaged by the tongues 10 which ultimately rest against the flat portions of the hexagonal part 11 and effectually retain the capsule in place. Moreover, regardless of how far 5 said capsule is inserted, the outer portion of the fuse 16 is certain to be frictionally engaged by and make good electrical contact with one of the spring tongues 10, so that even if said plug should not be forced 10 to its full extent into the body, a circuit is none the less certainly established from the contact 15 through the fuse 16 to one of the tongues 10 and thence to the threaded shell 9.

15 It is noted that in addition to the corrugations or teeth formed in the outer face of the flange 2 at one end of the body 1, a second set of substantially radial corrugations 18 is formed in the opposite or overhanging 20 part of said flange and since the flange 7 of the ring 6 loosely fits over this flange, any gases or hot air formed within the cavity of the fuse plug upon blowing of the fuse, are free to escape through the channels thus 25 provided. While as described, the capsule is firmly held in the fuse plug body, it may be withdrawn when desired to permit of the inspection of its fuse or if the latter be broken or defective, it may be replaced by 30 a new capsule.

I claim:

1. The combination of a hollow fuse plug body including a threaded shell open at one 35 end; a plurality of spring tongues connected to the shell and extending into the hollow of the body from the open end thereof; and a capsule removably mounted in said hollow of the body having a fuse positioned to electrically engage any one of the spring 40 tongues.

2. The combination of a hollow fuse plug body having polygonal cavity; a threaded shell on the body; a plurality of spring tongues connected to said shell extending 45 into the cavity of the body from one end thereof respectively adjacent its walls; and a capsule removably mounted in the cavity having a fuse positioned to engage any one of the spring tongues.

3. The combination of a fuse plug body 50 including an insulating supporting structure having a longitudinally extending cavity; a threaded shell mounted on the body and flanged to extend over one end thereof; spring tongues on the flange extending into the cavity of the body; with a capsule removably mounted in the cavity of the body and including a fuse removably engaging any one of the tongues. 55

4. The combination in a fuse plug of a 60 hollow insulating body having a flange at one end formed with substantially radial teeth on its opposite faces; a cover for the flanged end of the body; a ring flanged at both edges to project over the two sets of 65 teeth of the body and retain the cover in position; with a threaded shell mounted on said body.

5. The combination in a fuse plug of a 70 body of insulating material having a cavity formed with cylindrical and polygonal portions; with a threaded shell mounted on the body having a series of spring tongues extending into the polygonal portion of the 75 cavity thereof.

6. A fuse capsule consisting of a body of insulating material having a cylindrical portion, a flange and a polygonal portion intermediate said first two parts; and a fuse in the capsule having a part extending over 80 the surface of the polygonal portion thereof.

7. The combination in a fuse plug of a body of insulating material having a longitudinally extending cavity formed with cylindrical and polygonal portions; a threaded 85 shell on said body having spring tongues extending into the polygonal portion of the cavity thereof; with a capsule consisting of an insulating body formed with cylindrical and polygonal portions shaped to fit the 90 corresponding parts of the body; and a fuse on said capsule having a portion extending over one side of its polygonal portion in position to cooperate with and electrically engage one of the spring tongues of the body. 95

In witness whereof I affix my signature.

HENRY T. PAISTE.
